UNITED STATES PATENT OFFICE

ALMOND H. SNYDER, OF LANCASTER, NEW YORK, ASSIGNOR TO GOULD STORAGE BATTERY COMPANY, INC., OF NEW YORK, N. Y., A CORPORATION OF NEW YORK

STORAGE-BATTERY CONTAINER

Application filed April 8, 1926. Serial No. 100,588.

This invention relates to containers and, more particularly, to such adapted to enclose storage batteries.

The principal object of this invention, generally considered, is to provide an enclosed container for storage batteries and the like having a gas and liquid tight joint between the lid and body or at other openings in such container.

10 Another object of the invention is to provide a gas and liquid tight joint for such containers that will seal under the action of the weight of the lid alone.

15 A further object of this invention is to provide a gas and liquid tight joint that may be cheaply constructed and, at the same time, will be positive in its action.

20 Other objects and advantages of the invention will become apparent as the description proceeds.

It has long been recognized as desirable to combine in one cabinet, radio apparatus and the batteries supplying the necessary power therefor. One of the objections to the use 25 of a storage battery for this purpose has hitherto been the difficulty of protecting the delicate metal parts of the radio apparatus from the corroding action of the minute quantities of sulphuric acid in the gas given off 30 during the operation of the battery. To properly isolate the battery from the rest of the apparatus, it is necessary that it be enclosed in a container sealed against the escape of gas and liquid from the battery into the cabinet.

35 In making a container of such a character, the difficulty has been to secure an effective seal between the lid and the body of the container. To finish the contact edges of these parts with sufficient accuracy to insure a seal 40 is both difficult and costly especially with the moulded containers in common use. Even when a sealing strip of felt is used, it has been necessary to draw the lid and body together with thumb screws or equivalent means 45 in the endeavor to secure a seal at all points of the joint. Carelessness on the part of the radio operator in failing to properly tighten the securing means has frequently resulted in serious injury to the radio apparatus. It is 50 desirable to produce a container with seal-

ing means that will effectively close the joint even should the operator fail to secure the usual fastenings.

My invention relates to such means and is shown in a preferred form in the accompanying drawings in which:

Figure 1 is a side elevation of a battery container, partly in section, to illustrate the joint between the lid and the body of such a container.

Figure 2 is an enlarged vertical sectional view of the lid closed against the adjacent edge of the body.

Figure 3 is a similar view of the lid separate from the body.

Referring to the drawings in detail, like parts being designated by like reference characters, there is shown a typical power unit, such as is used in radio cabinets, involving a container for the battery elements and the like comprising a body 1 and a lid 2.

The body 1 of the container, formed usually by moulded acid-resisting material, is provided with a stepped rim having a horizontal face 3 and a vertical face 4 for receiving the flange 5 of the lid 2 so as to form a telescoping joint or lipped engagement. The flange 5 is provided with a horizontal face 6 opposed to the face 3 of the body rim. Interposed between the faces 3 and 5 is a sealing strip 7 preferably formed of soft rubber securely fastened to the face 6 of the lid. This strip is preferably substantially triangular in cross section and is so arranged as to have a surface in contact with the vertical face 4 and an edge in contact with the horizontal face 3 of the body rim. It is to be noted that the weight of the lid 2 is supported by the edge of the sealing strip 7 in contact with the face 3. This edge yields until the bearing surface of the sealing strip 7 in contact with the face 3 is sufficient to support the lid and in so yielding, any inequalities or irregularities of the surface 3 are readily compensated for by the yielding material 7 and a gas and liquid tight joint secured between the lid and the body.

In the power unit chosen to illustrate this invention, an electrolytic rectifier 8 is placed in an end compartment adjacent an end wall 100

of the container 1 in which are provided
5 ventilating apertures 9 and 10 to direct such
gases as may be generated away from the
apparatus with which the power unit is as-
sociated. The rectifier 8 may be separated
from the walls of the compartment by ribbed
metal plates or separators 11 to provide for
the ready passage of air and so insure proper
10 ventilation of the container and cooling of
the rectifying unit.

10 To accommodate differences in design of
containers, a number of changes may be made
in the form of the joint without departing
from the spirit of my invention as long as
15 there is an edge and a surface contact be-
tween the lid or the body and the yielding
sealing means whereby any inequalities in
the rigid lid or body member, as the case may
be, will be compensated for by the yielding
20 material of the sealing means.

I claim:

1. A container for battery elements and a
rectifier in a single unit comprising a body,
a lid and an interposed sealing strip of soft
25 rubber, said lid having a lipped engagement
with the body, said body having a stepped
rim for receiving the lid, said sealing strip
being secured to said lid and having a sur-
face contacting with the vertical face of said
30 stepped rim and an edge in contact with the
horizontal face of said rim.

2. A container for battery elements and
the like comprising an integral body with a
stepped upper portion, an integral flanged
35 lid adapted to telescope with said stepped
upper portion, and interposed sealing means
of pliable rubber secured to the flange of
the lid and having an edge and surface in
contact with the stepped portion of the body.

40 In testimony whereof I affix my signature.
ALMOND H. SNYDER.
